Primary Examiner — Ruth McInroy(74) *Attorney, Agent, or Firm* — Hodgson Russ LLP**CLAIM**

The ornamental design for a swimming pool vacuum, as shown and described.

DESCRIPTION

FIG. 1 is a front-right-top perspective view of a swimming pool vacuum showing my new design;

FIG. 2 is a rear-right-bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate unclaimed portions of the swimming pool vacuum that form no part of the claimed design.
